UNITED STATES PATENT OFFICE.

GEORGE L. KESTNER, OF PITTSBURG, PENNSYLVANIA.

BOTTLE-PROTECTOR.

SPECIFICATION forming part of Letters Patent No. 770,528, dated September 20, 1904.

Application filed May 12, 1904. Serial No. 207,685. (No model.)

To all whom it may concern:

Be it known that I, GEORGE L. KESTNER, a citizen of the United States of America, residing at Pittsburg, in the county of Allegheny and State of Pennsylvania, have invented certain new and useful Improvements in Bottle-Protectors, of which the following is a specification, reference being had therein to the accompanying drawings.

10 This invention has relation to bottle-protectors, and has for its object the provision of novel means whereby when a bottle is being opened or uncorked the bottle and its contents will be protected, also the person opening the

15 bottle. Another object of my invention is to provide a protector for bottles which is adapted to surround the bottle and protect the same while it is being handled and in case the bottle should become broken to protect the party opening the same from being cut or otherwise injured from the bottle.

20 Novel means is provided whereby a bottle may be supported within the protector and also means whereby said protector may be readily placed upon the bottle and quickly removed therefrom after the same has been opened.

25 The many advantages of my improved bottle-protector will be apparent from the following description, taken in connection with the drawings, wherein like numerals of reference indicate like parts throughout the several views, in which—

30 Figure 1 is a perspective view of my improved bottle-protector, showing a part of the same having a bottle placed therein. Fig. 2 is a front view of the same, and Fig. 3 is a transverse sectional view taken on the line

40 $x x$ of Fig. 2.

45 Referring to the drawings accompanying this application, the reference-numeral 1 indicates an ordinary form of bottle which comprises a body portion 2, and a neck 3, this neck being provided with an annular enlargement 4 around its upper edge, as shown in Fig. 1 of the drawings. The bottle is incased by one-half of my improved bottle-protector.

The reference-numeral 5 indicates one section of my improved bottle-protector, and the 50 reference-numeral 6 the other, these halves being hinged together, as indicated at 7 and 8, the hinges being of any preferred form which is advantageous to the general construction of the protector. These two half-sections comprising my improved bottle-protector are shaped to conform in outline to the contour of a bottle, each half-section comprising a semicircular base portion 9, which is formed integral with the side 10, this side being also 60 semicircular in form and tapers, as indicated at 11, to a contracted portion which corresponds to the general contour of the ordinary bottle-neck. Each of these half-sections 5 and 6 is preferably formed or cast from one piece 65 of metal, whereby the cost of manufacture is reduced to a minimum, and upon the base portion 9 of each half-section I secure a semicircular gasket 12, and I also secure by any desired means another semicircular gasket, 14, in each 70 of the halves 5 and 6, these gaskets 14 being placed intermediate the length of the protector and preferably at the point where the sides commence to taper to the contracted neck portion 11. By employing these gaskets 75 the bottle when placed in the protector is cushioned therein, and any jar upon the bottle is taken up by the gaskets and the bottle thoroughly protected from becoming broken or cracked.

80 When it is desired to open the bottle or withdraw a cork, the protector is placed around the bottle, as shown in Figs. 2 and 3 of the drawings, the half-sections 5 and 6 of the protector being held together at the neck portion 85 by the person opening the bottle, and it will be seen that in case the bottle should become cracked or the neck portion should snap off the contents of the bottle will be saved and the party opening the same will be protected from 90 the broken glass or cracked edges of the bottle.

While I have herein shown the preferred form of constructing my improved protector, it is obvious that any form of clasp may be readily employed for securing the two half-sections together, and the arrangement and

general position of the gaskets mounted in the protector may be changed without departing from the scope of the invention.

What I claim, and desire to secure by Letters Patent, is—

In a device of the character described, the combination with a bottle of two semicircular sections hinged together, each of said sections comprising a semicircular casing having a base portion, the upper ends of said semicircular casings being tapered, semicircular gaskets mounted in said casings and secured thereto,

two of said semicircular gaskets surrounding the body of the bottle and two surrounding the corner or edge formed by the meeting of the bottom and side walls, substantially as described and for the purpose set forth. 15

In testimony whereof I affix my signature in the presence of two witnesses.

GEORGE L. KESTNER.
